Inventor
Attorney

UNITED STATES PATENT OFFICE.

TOM HUSTON, OF COLUMBUS, GEORGIA.

DISPLAY STAND.

Application filed December 4, 1925. Serial No. 73,160.

- My invention relates to a display stand for merchandise, and particularly for small package goods such as salted peanuts, candy, chewing gum and the like.
- 6 The object of my invention is to provide a combined jar holder and advertising display stand which will not only hold the glass jar containing the merchandise securely in position on the counter but will also serve 10 to display both permanent and changeable advertising matter relative to the merchandise so as to make the display more attractive and increase the sale of the articles displayed.
- 15 My invention further comprises the novel details of construction and arrangements of parts, which in their preferred embodiment only are illustrated in the accompanying drawings which form a part of this specification, and in which:—
- Fig. 1 is a vertical cross-section through a show case with my improved display stand shown partly in side elevation and partly in section.
- 25 Fig. 2 is a perspective view of the base or stand with its advertising displays. Similar reference numerals refer to similar parts throughout the drawings.
- In the embodiment of my invention illustrated, I show a glass jar or container 1 having a removable top 2 and which is adapted to be filled with the goods to be displayed. This jar will fit snugly in a seat 3 provided in a base or stand 4, the 30 seat being formed by a downwardly and inwardly curved flange carried by an annular substantially vertical flange 5. I cast integral with the base 5 a horizontal forward extension or neck 6 adapted to have its 35 outer edge overhang the front edge of the counter 7 upon which the device is placed. This neck 6 carries a wedge shaped extension 8 which is made wide enough to carry on its upper bevelled surface suitable permanent display matter, such as a trade-name 40 for the goods on display in the jar. The outer forward edge of the extension 8 is integral with a downwardly depending backing plate 9 having attached to its front face a window frame 10 formed with a top 50 slot 11 through which an interchangeable advertising sign or display card 12 is adapted to be dropped and to be displayed in vertical position in the frame which hangs parallel with and close to the front 13 of the 55 counter. All of the base as thus far described is preferably in the form of an integral casting and is suitably ornamented so as to make a very attractive and effective display.
- Though I have described with great particularity the details of the embodiment of the invention herein shown, it is not to be construed that I am limited thereto, as changes in arrangement and substitution of 60 equivalents may be made by those skilled in the art without departing from the invention as defined in the appended claims.
- Having thus described my invention, what I claim as new and desire to secure by Letters Patent, is:—
1. An advertising display stand, comprising the horizontally disposed seat for a display container for wares, and a depending front flange adapted to overhang 75 the counter and provided with means for the reception of a display.
2. An advertising display stand according to claim 1, in which the flange is connected with the seat by a neck and adapted 80 to receive an advertising display card.
3. An advertising display stand comprising a glass jar, and a base providing a countersunk seat for a display jar adapted to rest on a counter, an integral neck adapted 85 to overhang the counter, and a dependent display card holder adapted to underhang from said neck and to be disposed in front of the counter.
- In testimony whereof I affix my signature.

TOM HUSTON.
